UNITED STATES PATENT OFFICE.

WINFIELD S. THOMAS, OF EAST DIXFIELD, MAINE.

LADDER.

SPECIFICATION forming part of Letters Patent No. 257,411, dated May 2, 1882.

Application filed March 15, 1882. (No model.)

To all whom it may concern:

Be it known that I, WINFIELD SCOTT THOMAS, of East Dixfield, Oxford county, Maine, have invented a new and Improved Ladder, of 5 which the following is a full, clear, and exact description.

The invention consists in a novel combination and arrangement of parts, as hereinafter described, and pointed out in the claims.

10 Reference is to be had to the accompanying drawings, forming part of this specification, in which similar letters of reference indicate corresponding parts in both figures.

Figure 1 is a front elevation of my improved 15 ladder as adjusted for the greatest height, with some of the parts in section; and Fig. 2 is a side elevation of the improved ladder as when arranged in the self-supporting position.

A represents the side bars, and B the steps, 20 of the lower section, to one of which side bars I apply an extension-foot, C, for use, as indicated in the drawings, upon uneven ground, the said foot-piece being arranged to slide in a clip, D, attached to the side bar a suitable 25 distance above its lower end, and also being slotted at E below said clip to slide along the clamp-bolt F, which is firmly secured in the side bar a short distance above its lower end. The surfaces of the side bar and the extension- 30 foot are notched or serrated, as seen through slot E in Fig. 2, to prevent them from slipping on each other when clamped in position by the bolt.

The top section of the ladder is composed of 35 the side bars G and steps H. It is made in A-shape in order to have the side bars unite in a point, I, at the top for greater strength and for the resting of the top better on the ground when used as a brace to the bottom 40 section, as seen in Fig. 2, and a spike of metal, J, is inserted for the better security of the foot of the brace. To accommodate this pointed shape of the upper section the lower section is also made convergent upon the same angle, so 45 that where the side bars of the two sections overlap each other at the joint they will match each other correctly; and the base of the upper section is made lower than the top of the lower section to receive said top between its 50 side bars as the best arrangement for lateral stiffness. The top section is pivoted at the

lower ends of its side bars to the lower section by the rod K as much below the top of said lower section as it is desired that the two sections shall overlap each other, and on this 55 pivot the top section turns when shifted from one condition to another, the ends of the bolt being riveted or otherwise permanently secured.

For a locking device to connect the two sections substantially in the condition of the long ladder a rod, L, which also serves for a step, is passed through side bars G in slotted holes M, which are so located with reference to the upper ends of side bars A that when said top 60 section is adjusted in line with the bottom section the rod will drop into notches N, made for the purpose, in the upper ends of the side bars of said bottom section and lock the two sections in that position. To secure the rod in 65 the notches N pins O are inserted in holes through side bars G traversing the slotted holes M just over the rod to prevent it from being displaced by accident.

By this contrivance a substantial and useful 70 ladder is provided, capable of service as an ordinary ladder, also as a self-supporting one, and also as benches for scaffolding and the like.

Having thus described my invention, I claim 75 as new and desire to secure by Letters Patent—

1. In a ladder, the combination, with the lower section provided with the notches N in the ends of its side bars A, of the upper section pivoted to the said lower section and having its side bars G provided with the slots M, 80 and the rod L, working in the said slots and adapted to be locked in the notches of the side bars of the lower section, substantially as and 85 for the purpose set forth.

2. In a ladder, the combination, with the convergent side bars A of the lower section, having their upper ends provided with notches N, of the convergent side bars G of the upper section, provided with the slots M and the spike J, the rods K-L, and the pins O, substantially as and for the purpose set forth.

WINFIELD S. THOMAS.
